Primary Examiner — Robert M Spear*Assistant Examiner* — Darcey E Heflin(74) *Attorney, Agent, or Firm* — Cislo & Thomas, LLP; Kelly W. Cunningham, Esq.(57) **CLAIM**

I claim the ornamental design for a bottle cap, as shown and described.

DESCRIPTION

FIG. 1. Is a perspective view of one embodiment of my bottle cap;

FIG. 2. Is a right side view thereof;

FIG. 3. Is a left side view thereof;

FIG. 4. Is a front side view thereof;

FIG. 5. Is a back side view thereof;

FIG. 6. Is a top view thereof; and,

FIG. 7. Is a bottom side view thereof.

The broken lines show portions of the bottle cap that form no part of the claimed design.
